(57) **CLAIM**

I claim the ornamental design for a sound maker for use on a bicycle, as shown and described.

DESCRIPTION

FIG. 1 is a perspective view of the sound maker for use on a bicycle showing my new invention;

FIG. 2 is another perspective view thereof;

FIG. 3 is another perspective view thereof;

FIG. 4 is another perspective view thereof;

FIG. 5 is a front elevation thereof, and the rear elevation is identical;

FIG. 6 is a left side elevation thereof, and the right side elevation is identical;

FIG. 7 is a cross sectional view thereof along line 7-7 in FIG. 6;

FIG. 8 is a bottom plan view thereof; and,

FIG. 9 is a top plan view thereof.
